UNITED STATES PATENT OFFICE.

ELIAS ISRAEL, OF NEW YORK, N. Y.

DESIGN FOR IMITATION-STRAW-BRAID FABRIC FOR HATS.

47,397.

Specification for Design.

Patented June 1, 1915.

Application filed March 20, 1915. Serial No. 15,962. Term of patent 3½ years.

To all whom it may concern:

Be it known that I, ELIAS ISRAEL, a subject of the Czar of Russia, residing at New York city, county of New York, and State of New York, have invented a new, original, and ornamental Design for Imitation-Straw-Braid Fabric for Hats, of which the following is a specification, reference being had to the accompanying drawing, forming part thereof.

The drawing is an enlarged front or face view of a piece of fabric embodying my invention.

More fully stated, the design is for a hat

fabric formed from braid made of thread woven or braided to imitate or have the appearance of straw.

I claim:

The ornamental design for imitation straw braid fabric for hats, as shown and described.

In witness whereof, I have hereunto set my hand in the presence of two witnesses.

ELIAS ISRAEL.

Witnesses:

C. FRANCISCO,
PETER C. MANY.
